CONSTRUCTION OF SHIRTS FOR MEN

Ethel M. Roseen, Minneapolis, Minn.

Application August 9, 1946, Serial No. 689,447

3 Claims. (Cl. 2—115)

1.

My invention relates to construction of shirts for men and has for its object to eliminate the yoke customarily employed at the top of the shirt and provide a construction which gives a smooth appearance of the shirt across the back under the collar.

Shirts as constructed at the present time embody a top yoke to which the collar is attached and also the body of the shirt. The use of the yoke, has been with the intention and idea of so fitting the shirt along the back between the shoulders and running under the collar that it will lie smooth and flat. Actually, with the vast majority of individuals, where the shirt is not made to order, this does not take place, but there is a bunching of the shirt at the collar. This bunching is objectionable, since it gives the effect of a poor fit to the shirt when the wearer is going without a coat and it will show through the coat where a light coat is employed, giving the effect of poor fit at the collar of the wearer's coat.

Even with made-to-order tailored shirts difficulty has been experienced in bunching and obviously relatively few men are in a position to pay the much higher price of tailored shirts.

I have discovered a very simple manner of completely avoiding this unsatisfactory and unsightly bunching effect, which is applicable to all sizes of men.

This new construction comes from entirely eliminating the top yoke and effecting fitting across the back between the upper slopes of the shoulders by employing toward the upper extensions of each of said slopes a double, slightly tapered fold running downwardly from their upper ends along lines where the folded parts substantially meet and stitched down vertically therefrom for a short distance and thereafter running freely for complete opening before the waistline is reached.

This arrangement leaves a band of the material between the two vertical sets of stitching which extends directly down from the union thereof with the front panels of the shirt at the shoulder line.

It is an object of my invention, therefore, to provide a shirt construction which has no yoke across the back connected with the point of union of the collar to the back, and which, for avoiding use of the yoke, provides at each side a double folded pleat substantially in contact along its inner edges and there stitched for a short distance along a substantially vertical line and

2.

thereafter free and expandible toward the belt line of the garment.

The full objects and advantages of my invention will appear in connection with the specification hereinafter given, and its novel features by which the aforementioned highly useful and advantageous results are obtained will be particularly pointed out in the claims.

In the drawings illustrating an application of my invention in one of its forms:

Fig. 1 is a back view of a shirt as the same is worn showing the manner in which the double pleats are provided and the straight, smooth appearance of the shirt back to and under the collar.

Fig. 2 is a side elevation view of my improved shirt as shown in Fig. 1.

Fig. 3 is a similar side elevation view of an old style shirt showing the manner in which the shirt bunches below the collar.

Fig. 4 is a fragmentary view on an enlarged scale of one of the double pleats adjacent the shoulder union between the back and one of the front pieces of the shirt.

Fig. 5 is an enlarged sectional view taken on line 5—5 of Fig. 4.

Fig. 6 is an enlarged sectional view taken on line 6—6 of Fig. 4.

Fig. 7 is an enlarged sectional view taken on line 7—7 of Fig. 4.

As illustrated, the front panels, similar to panel indicated at 10 in Figs. 2 and 4, are or may be of normal construction, united, as indicated at 11 in Figs. 2 and 4, with the shoulder extension 13 of the back, indicated at 13 in Fig. 4, and at 13 and 14 in Fig. 1.

Running from the seams 11 toward the upper part of the shoulder slopes are double pleats 15 and 16, in the form of inverted box pleats, as shown in Figs. 1 and 4. These double pleats are sewed to a point indicated at 17 in Fig. 4, and have their folded edges 18 and 19 substantially in contact and are held by stitching 20 and 21 extending vertically through the fabric of shoulder extension 13 and are held in three layers 22, 23 and 24 at that side of the folds 18 and 19.

The under layers of fabric 23, 23' and 24 extend into the folds 25 and 26, and, as in Fig. 5, the three layers 22, 23 and 24 lie flat on one side of the fold 18, and layers 24, 23' and 22' lie flat on the other side of fold 21.

The shoulder extensions 13 and 14 are taken from what amounts to a central back panel 27 which extends between the vertical meeting edges 15 and 16 of the two folds 18 and 19, as clearly

shown in exaggerated form in Fig. 5. The rows of stitches 20 and 21 extend in parallel relation to the point 17 where the stitching ends.

As shown in Fig. 6, the rows of stitches 20 and 21 are here discontinued, and the folds 18 and 19 are separated by a slight gap 28. The layers of cloth 22, 23 and 24, at the point of section 6-6, are thus free to begin to spread from the unsewed fold portions 18 and 19.

As shown in Fig. 7, this spreading has substantially increased, the edges 18 and 19 now being separated by a substantial gap 29. And, referring to Fig. 1, it will be apparent that the spreading of the folds 18 and 19 continues to points 30 and 31 where the spreading merges into the normal shirt fullness at 32 just above the customary belt 33.

Figs. 1 and 2 show the manner in which the back panel 27 hangs straight from the collar, leaving a perfectly smooth transverse stretch of material extending from under the bottom edge 34 of the collar 35.

Fig. 3 shows the objectionable bunch fold 36 at the back of shirts and below the collar caused by the customary yoke construction 37. A great deal of experimentation has been carried out by shirt manufacturers in an effort to overcome this objectionable difficulty, but the yoke has continued to be employed with different characteristics and widths, and always, for a considerable number of wearers, the bunching occurs.

I have found that when the rear panel of the shirt is directly connected to the front panels at the crests of the shoulders of a wearer, and the upper extremity of the rear panel is made to fit snugly above the shoulder blades by means of the pleats, the excess lateral fullness of the rear panel is transferred from the area above the shoulder blades where it causes the formation of the horizontally extended longitudinal fold in conventional shirt panels, as shown at 36 in Fig. 3, to the area between the shoulder blades and extending to the lower extremity of the rear panel to provide a fullness between the tips of the shoulder blades and extending below the waistline. This construction provides a neat appearance immediately below the collar and also avoids any binding effect between the shoulder blades and extending below the waistline, which would result if the pleats extended in a secured manner below the shoulder blades.

The advantages of my invention have been substantially pointed out in the preceding specification. The fundamental and primary advantage comes from the fact that with practically every type of figure the construction of my invention does eliminate bunching at the top of the back and below the collar. In other words standard ready-made shirts employing my invention, which have the proper size neck band and shoulder width, will have the back panel 27 thereof hang smooth, unbunched and unwrinkled from the bottom of the collar down the back to the shirt fullness at the waist line.

A further substantial advantage comes from the fact that a shirt employing my invention may

be manufactured more cheaply than the customary yoke shirts, and for that reason will cheapen the cost of the shirt to the ultimate consumer.

Another marked advantage of my invention resides in the freedom and looseness of the material about the waist of a shirt employing my invention.

I claim:

1. A man's shirt construction, comprising front panels, a collar, a unitary back panel joined to the front panels at the crest of the shoulders of a wearer, and a pair of pleats extending substantially vertically in parallel relation to each other from adjacent the outer limits of the collar and the upper slopes of the shoulders, said pleats commencing at the point of junction of the back panel with the front panels and terminating at the areas covering the tips of the shoulder blades to transfer excess fullness in the back panel from the area above the shoulder blades to the area below the shoulder blades and extending to the lower extremity of the back panel.

2. A man's shirt construction, comprising front panels, a collar, a unitary back panel joined to the front panels at the crest of the shoulders of a wearer, a pair of inverted box pleats extending substantially vertically in parallel relation to each other from adjacent the outer limits of the collar and the upper slopes of the shoulders, and a row of stitches securing the opposite sides of the box pleats and commencing at the point of junction of the back panel with the front panels and terminating at the areas covering the tips of the shoulder blades of the wearer to transfer excess fullness in the back panel from the area above the shoulder blades to the area below the shoulder blades and extending to the lower extremity of the back panel.

3. A man's shirt construction, comprising front panels, a collar, a unitary back panel secured to the front panels at the crests of the shoulders of a wearer, and a pair of inverted box pleats formed in the back panel to transfer excess fullness of the material forming the back panel from the area immediately beneath the collar to the area between the shoulder blades and extending below the waistline, said pleats being formed in only one end of the back panel commencing at the junction of the back panel with the front panels and terminating adjacent the shoulder blades of a wearer.
